WITNESS:

UNITED STATES PATENT OFFICE.

JOSÉ NEFTALI DELGADO, OF READING, PENNSYLVANIA.

PROPELLER SCREW.

Application filed March 22, 1923. Serial No. 626,962.

To all whom it may concern:

Be it known that I, José NEFTALI DELGADO, a citizen of Mexico, residing at Reading, in the county of Berks and State of Pennsylvania, have invented new and useful Improvements in Propeller Screws, of which the following is a specification.

This invention relates to propelling means for boats of different kinds, the general object of the invention being to provide means for propelling the boat by turning a crank which operates the propeller so that it is not necessary to use oars.

Another object of the invention is to so arrange the propeller parts that the blades will be feathered when they are moving in the direction the boat is moving so as to offer the least resistance to the water.

This invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:—

Figure 1 is a plan view showing the invention in use upon a row-boat.

Figure 2 is a sectional view taken transversely through Figure 1.

Figure 3 is an enlarged view of the device itself.

Figure 4 is a section on line 4—4 of Figure 3.

Figure 5 is a section on line 5—5 of Figure 3.

Figure 6 is a detail view showing the cammed head and the shank of one of the propeller blades in section and the relation of the shank with cammed surface.

45 In these views 1 indicates a bracket which is provided with the long vertical bearing 2 and the short horizontal bearing 3, the bearing 2 carrying the vertical propeller shaft 4 and the bearing 3 carrying the shaft 5 which is provided with a handle 6. These shafts are geared together by the gears 7. The lower end of the propeller shaft 4 has connected therewith an enlarged head 8 which has a transverse hole 9 passing there-

55 through which rotatably receives the shaft 10. The propeller blades 11 have their

shanks 12 securely mounted on the ends of this shaft at right angles to each other and these shanks are of oval shape in cross section, as shown. The lower end of the bearing 2 has an enlargement 2' thereon which carries a cam 2'', which, when engaged by the oval shank 12 of the blade, will turn the same and the blade and thus feather the blade and permit it to pass through the water with the least resistance. These parts are so arranged that when the blade is traveling outwardly and rearwardly it will offer the maximum resistance to the water and thus act to propel the boat but when it is traveling forwardly it will be feathered and thus not interfere with the passage of the boat through the water. It will be seen that power is imparted to the propeller blade by turning the shaft 5 by means of the handle 6 which will rotate the shaft 4 through means of the gear 7. As many of these devices can be used as necessary and they are detachably connected with the boat by means of the plates 13 which are fastened to the boat and which have undercut beads 14 thereon engaging grooves 15 or like shape in the bracket 2. In this way the devices can be pulled upwardly and detached from the boat and placed inside the boat when not in use.

It is thought from the foregoing description that the advantages and novel features of my invention will be readily apparent.

I desire it to be understood that I may make changes in the construction and in the combination and arrangement of the several parts, provided that such changes fall within the scope of the appended claims.

What I claim is:—

1. In combination with a boat, a plate thereon having an undercut bead, a bracket having a groove designed for fitting engagement with the bead, a pair of shafts carried by the bracket, gears connecting the shafts together, a handle connected with one shaft, a transversely disposed shaft connected with the other shaft, propeller blades rigidly connected with the transversely disposed shaft and a cam carried by the bracket and engaging portions of the propeller blades for feathering them during a part of the revolution.

2. The combination with a boat, of a plate secured thereto and being provided with a bead having undercut side walls, a bracket having a groove designed to fit the walls of

the bead and being provided with horizontal and vertically disposed bearings, a shaft mounted for rotation in each of these bearings, manually operated means for simultaneously rotating the shafts, an apertured enlarged head formed on the lower end of the vertically disposed shaft, a cammed surface formed on the enlarged lower end of the wall of vertically disposed bearings, a trans-

versely disposed shaft mounted for rotation in the aperture of the head, propeller blades carried by the transversely disposed shaft, and oval shaped shanks forming the inner ends of the blades and adapted for rotary engagement with the cammed surface as and for the purpose specified.

In testimony whereof I affix my signature.

JOSÉ NEFTALI DELGADO.
